CLAIM

The ornamental design for a door for dishwasher as shown and described.

DESCRIPTION

FIG. 1 is a front perspective view of the door for dishwasher showing our new design;

FIG. 2 is a front view thereof;

FIG. 3 is a back view thereof;

FIG. 4 is a left side view thereof where the right side view is a mirror image;

FIG. 5 is a top plan view thereof;

FIG. 6 is a bottom plan view thereof;

FIG. 7 is a partial enlarged view of the area '7' as identified in FIG. 1;

FIG. 8 is a front perspective view in a condition that the handle has been flipped inside;

FIG. 9 is a front view of FIG. 8;

FIG. 10 is a back view of FIG. 8;

FIG. 11 is a left side view of FIG. 8 where the right side view is a mirror image;

FIG. 12 is a top plan view of FIG. 8;

FIG. 13 is a bottom plan view of FIG. 8; and,

FIG. 14 is a partial enlarged view of the area '14' as identified in FIG. 8.

The broken lines depict portions of the door for dishwasher that form no part of the claimed design. The dash-dot broken lines shown in FIG. 1 and 8 indicate cutoff boundaries for the enlarged detailed portion views and form no part of the claimed design.
